Walter Bryant of Boston Mass.
Letters Patent No. 237. Dated June 4. 1850.

The Schedule referred to in these Letters Patent and making part of the same.

To all Persons to whom these Presents shall come:

Be it Known, that I, Walter Bryant of Boston in the County of Suffolk and State of Massachusetts, have invented or produced a new and useful design for an Umbrella Stand, and I do hereby declare that the said new design is fully described and represented in the following specification and accompanying drawings, to which reference is hereinafter made.

Of the drawings, Fig. 1. is an elevation of my newly designed Umbrella Stand, Fig. 2 is a top view of the same, and Fig. 3 is a horizontal section taken in the plane of the line A. B. Fig 1.

My new design consists of two branches of grape or rustic vine a a a a a &c. b b b b &c cast in iron and twisted round each other around the top edge of the basin or vessel c c, in which the handle of the Umbrella is to rest, then at the centre of the back of said edge, the said branches rise vertically crossing each other at several intervals, so as to form the stem and handle, the tendrils d d - d d twisting together in the centre of the largest opening e e, as shown in Fig. 1. At a proper height, two branches f f - f f project out horizontally from the vertical stem of the stand, and are turned round so as to form the several looped spaces g g - g g - g g as shown in Fig. 2.

Having thus described my new design I shall state my claim as follows:-

What I claim as my production and desire to have secured to me by Letters Patent, is the new design for an Umbrella Stand, hereinabove described, consisting of branches of a grape or rustic vine, cast in a twisted form about the basin and then rising vertically and crossing each other to form the stem, from which other branches project horizontally and are turned so as to form the loop holes g g - g g &c, all as above set forth and represented in the accompanying plate of drawings.

Boston May 21st 1850.
